UNITED STATES PATENT OFFICE.

VASIL MACKAY, OF WASHINGTON, DISTRICT OF COLUMBIA.

MECHANICAL STOKING GRATE SUPPORT.

Application filed November 7, 1919. Serial No. 336,442.

To all whom it may concern:

Be it known that I, VASIL MACKAY, a citizen of the United States, residing at Washington, in the District of Columbia, have invented certain new and useful Improvements in a Mechanical Stoking Grate Support, of which the following is a specification.

My present invention relates to new and useful improvements in a furnace structure and more particularly to the support for the grate thereof.

The principal object of the invention is the construction of the grate support in such a manner that the dead plate, now commonly used in furnaces of the character illustrated may be eliminated.

Another object consists in constructing the grate support so that the same will be held in an inclined position, within the furnace, so that the fuel may be fed from the forward end to the rear end by means of sets of grate bars which are alternately operated in a manner to be later described.

A further object consists in the provision of a lip or projection, on the front of the furnace structure, adjacent the lower edge of the fuel opening, adapted to cooperate with the foremost grate bar to prevent fuel from sifting or dropping between the front of the furnace and grate bar.

With the above and other objects in view which will appear as the description proceeds my invention consists in the novel details of construction and arrangement of parts described and illustrated, and while I have illustrated and described the preferred embodiment of the invention it will be understood that such changes may be made in the construction and operation as fall within the scope of the appended claims.

In the accompanying drawings Figure 1 is a fragmental vertical section through the furnace structure showing the grate and supporting mechanism therefor in side elevation.

Figure 2 is a fragmental horizontal section through the furnace with the grate and supporting mechanism therefor shown in top plan.

Figure 3 is a fragmental enlarged vertical section through the front plate of the furnace structure and grate bars.

Figure 4 is a fragmental perspective of the front plate, of the furnace structure,

showing one end of the side grate supporting beam in position.

Figure 5 is a detailed fragmental perspective of one end of the side supporting beam:

Figure 6 is a fragmental perspective of the furnace structure with the grate supporting mechanism in position.

In the drawing A illustrates the masonry of the furnace structure having an opening in the front wall thereof adapted to be covered by means of the metal front plate B having the fuel opening C therein. The fire chamber is indicated at D and the metal front plate B is provided adjacent the bottom, with the transversely spaced openings E for removing ashes or gaining access to the ash pit for other purposes. The bridge wall is indicated at F and is of usual well known construction. It will be understood that the fuel opening C and the ash pit openings E will be covered by doors or if desired stokers of any well known construction may be secured over the fuel opening C.

The support for the grate bars consists of the longitudinally extending beams 10 which are transversely spaced within the furnace structure to receive the trunnions formed on the ends of the grate bars. Any number of rows of grate bars may be used but in the drawings I have illustrated four side bars 85 which will support two rows of grate bars and the opening C in the front plate B will be of sufficient length to allow the introduction of fuel on to both rows of the grate bars. As shown, more particularly in Figures 2 and 6, the intermediate side beams 10 will be arranged side by side. Each side beam 10 is formed with the leg 11 on one end and the angular extension 12 on the opposite end. The beams are so formed that the legs 11 will extend perpendicular where-as the angular extension 12 will be horizontal. The horizontal extensions 12 are adapted to be received in pockets 13 formed in the upper surface of a transversely extending girder 14 set in the front face of the bridge wall F at the lower end. Preferably the bridge wall overlies the top of the horizontal extensions 12 as more particularly illustrated in Figure 6, and the legs 11 are secured to the front plate B by means of bolts 15 or other suitable fastening means.

The beams are secured in any such position within the furnace structure, that the tops of the forward ends will lie flush with the lower 110

edge of the fuel opening C and will be inclined to support the grate bars in inclined position so that the fuel may be fed from the forward edge of the grate towards the 5 rear thereof.

A projection or lip 16 is formed on the inner face of the metal front plate B, adjacent the lower edge of the fuel opening C and when two rows of grate bars are used 10 this lip or projection will be cut away at the center, as more particularly illustrated in Figure 4, to receive the forward ends of the intermediate supporting beams. The grate bars are indicated at 17, and are provided on 15 their ends with trunnions adapted to be received in the sockets formed in the upper edges of the beams 10. The foremost grate bar 17 is adapted to rest in close proximity to the lip or projection 16 and will cooperate 20 therewith to prevent fuel from sifting between the front plate B and the grate bars. As shown, more particularly in Figure 3 of the drawings, the forward edge of the grate bar is arcuate in shape so as to remain in 25 close proximity to the lip or projection 16 during the swinging movement of the grate bar.

Operating levers 18 are pivotally connected to the front of the plate B, adjacent 30 the lower edge thereof, and are connected by means of links to the bars 19 which are secured to the depending arms 20 formed on the grate bars 17. Alternate grate bars are connected together so as to provide two sets 35 of grate bars which may be operated alternately to feed the fuel from the forward end of the grate towards the rear.

From the above detailed description it will be noted that I have provided supporting 40 means for the grate bars which will eliminate the use of the dead plate now commonly used in furnace structures of the character illustrated. At the same time it will be seen that the side supporting beams 10 are formed 45 with the perpendicular leg on one end and the horizontal extension on the opposite end so that when secured in the furnace they will be inclined from the forward edge towards the rear. This will support the grate bars in such position that fuel may be fed 50 from the forward end of the grate towards the rear. The lip or projection 16, formed on the inner face of the front plate B cooperates with the foremost grate bar so as to prevent 55 fuel from sifting between the front plate and foremost grate bar. The construction of my grate support is quite simple but at the same time supports the grate bars in a manner as to properly feed the fuel and 60 eliminate the dead plate.

Having fully described my invention what I claim as new and desire to secure by Letters Patent is:

1. In combination with a furnace having a fuel opening in the front wall thereof and a bridge wall formed with sockets, an inwardly extending lip formed at the lower edge of the fuel opening, a grate supported in the furnace with its forward end adjacent the fuel opening, said grate comprising inclined side beams each having a horizontal extension on the lower end received in one of the sockets formed in the bridge wall and a depending perpendicular leg formed on the opposite end and engaging the front wall of the furnace beneath the fuel opening, securing means passing through the legs and front wall of the furnace, swinging grate bars carried by the side beams, the forwardmost grate bar being in close proximity to the inwardly extending lip, and means for operating the grate. 65 70 75 80

2. In combination with a furnace having a fuel opening in the front wall thereof, a bridge wall having a cut out portion forming an over-hanging shoulder, a girder received in said cut out portion of the bridge wall and provided with recesses in the upper edge, a grate supported in the furnace with its forward end adjacent the fuel opening, said grate comprising inclined side beams each having a horizontal extension on the lower end received in one of the recesses in the upper edge of the girder and beneath the over-hanging shoulder of the bridge wall, 90 95 and a depending perpendicular leg on the upper end adapted to engage the front wall of the furnace beneath the front opening, securing means passing through the legs and front wall of the furnace, swinging grate bars carried by the side beams, and means for operating the grate bars. 100

3. In combination with a furnace having a fuel opening in the front wall thereof and a bridge wall formed with sockets, an inwardly extending lip formed at the lower edge of the fuel opening, downwardly inclined side beams having their upper ends in contact with the ends of the inwardly extending lip and secured to the front wall 105 and their lower ends supported in the sockets of the bridge wall, grate bars pivotally supported by the side beams, the uppermost grate bar lying in close proximity to the inwardly extending lip, and means for operating the grate bars. 110 115

In testimony whereof I hereunto affix my signature.

VASIL MacKAY.
